J. J. WOOD

VARIABLE NEUTRALIZING CONDENSER

Filed May 16, 1925

INVENTOR.
John J. Wood.

UNITED STATES PATENT OFFICE.

JOHN J. WOOD, OF DENVER, COLORADO.

VARIABLE NEUTRALIZING CONDENSER.

Application filed May 16, 1925. Serial No. 30,814.

My invention relates to the construction and mounting of a variable neutralizing condenser in a manner that will insure its proper operation in conjunction with a tuning condenser in a radio receiving apparatus, to automatically at any position of the tuning condenser, transfer around the audion tube to be neutralized, the correct amount of energy from the plate circuit to the grid circuit to exactly counteract the "feed back" current within the audion tube, as well as any external currents that might induce oscillations within the tube.

My variable neutralizing condenser is applicable to most radio frequency amplifying circuits that employ condensers for tuning. It imparts to any circuit in which it is used the stable characteristics that follow the use of fixed neutralizers, without the heavy losses which the use of these latter entail.

Its use enables the operation of the audion tube at its most efficient point at all times, without the exercise of effort or skill on the part of the operator.

It is understood that my invention covers any structural variations from this specification which are desirable to adopt it to any specific receiving apparatus.

The application of my invention to a commonly used radio frequency amplifying circuit is illustrated in Fig. 1 of the drawings. Detail views showing the construction and mounting which I prefer to use are shown in Fig. 2 which depicts a longitudinal section through my automatic neutralizing condenser mounted on a standard tuning condenser and operated from the same control, and in Fig. 3 which shows an end view of my automatic neutralizing condenser, illustrating the arrangement and extent of the plates.

In the circuit diagram, Fig. 1, the audion tube to be neutralized is indicated at *a*, the tuning condenser at *b*, and my variable neutralizing condenser at *c*. Its position, connection and operation in the circuit are exactly similar to other neutralizing condensers now in use and form no part of my invention, so that a detail description of these is unnecessary to its comprehension.

In the detail drawings, Figs. 2 and 3, the tuning condenser *b* is mounted in the usual manner upon a panel 1, its shaft 2 extending through the panel and having an operating knob 3 affixed to its outer end.

Operatively attached to the inner or op-

posite end of shaft 2 by means of a set screw 4 is a coupling 5, which is also pinned or otherwise fastened to shaft 6 of my automatic neutralizing condenser *c*. Shaft 6 projects through a boss formed in the center of a supporting plate 7, of dielectric material. Supporting plate 7 is mounted on an extension 8 of one of the supporting studs of tuning condenser *b* and serves to support and electrically insulate the parts of my automatic neutralizing condenser *c* and to maintain the alignment of shafts 2 and 6.

The stationary plates of my variable neutralizing condenser consist of two parallel sectors 9 and 9'. Soldered or otherwise affixed to plates 9 and 9' are bosses 10 and 10' respectively, adapted for screw threaded engagement with adjusting screw 11. That portion of adjusting screw 11 which is traversed by boss 10 is threaded in a left hand direction, while the portion traversed by boss 10' is threaded in a right hand direction, or vice versa. An operating knob 11^a is pressed onto an extension of adjusting screw 11, and it will be clear from the foregoing that rotation of knob 11^a and adjusting screw 11 in one direction will draw bosses 10 and 10', together with plates 9 and 9' toward each other, while the reverse rotation will move them away from each other.

Adjusting screw 11 is hollow and loosely fitted over mounting screw 12 which is threaded into supporting plate 7, thus permitting free rotation of adjusting screw 11 without endwise movement.

In order to preserve their correct alignment and insure that they will move only in a linear direction, plates 9 and 9' are perforated and adapted to slide freely over guiding studs 13 and 13', which are fastened into supporting plate 7.

The movable plate of my variable neutralizing condenser is formed of two or more sectors, 14 and 14', clamped against a shoulder on shaft 6 by means of a nut 15. By loosening nut 15 these sectors can be spread fanwise to form a large sector, or contracted to form a small one, for the purpose fully explained hereinafter.

Either the plate or the grid side of audion tube *a* is electrically connected to stationary plates through a binding post 16 formed on mounting screw 12. The opposite side of audion tube *a* is electrically connected to the movable plate 14 and 14'

through contact spring 17 and binding post 18, mounted on supporting plate 7.

Radio receiving sets have widely different characteristics. In order to make my variable neutralizing condenser as widely adaptable as possible, I have provided various adjustments which have been described and the purposes of which will now be explained.

A point exists in the range of signal frequencies at which oscillations will be induced in audion tube α , in any particular receiving set. This point is probably not the same in any two sets and may even vary with different tubes. Until this point is reached, no neutralizing device is necessary and its use introduces needless losses into the circuit.

By means of set screw 4 in coupling 5 between shaft 2 of the tuning condenser and shaft 6 of my variable neutralizing condenser movable plate 14 and 14' of the latter may be adjusted to enter the active space between stationary plates 9 and 9' at exactly the frequency that its use becomes necessary.

The range of frequencies through which a neutralizing condenser is necessary also varies with different sets, as does the necessary intensity of neutralizing action at particular frequencies. The spreading or contracting of sectors 14 and 14' composing the movable plate, facilitate the adjustment of my automatic neutralizing condenser to exactly co-operate with the individual audion tube to be neutralized, both in duration and intensity of its action.

The maximum intensity of necessary neutralizing action is also variable. The maximum capacity of my variable neutralizing condenser may be easily and accurately regulated by moving stationary plates 9 and 9' by means of adjusting screw 11. Turning this screw in a direction to decrease the distance between stationary plates 9 and 9' and movable plates 14 and 14', increases the maximum capacity of the condenser. Reverse movement of adjusting screw 11 has the opposite effect.

From the foregoing it will be clear that my invention provides a variable neutraliz-

ing condenser having a sufficient range of adjustments to adapt it to many receiving sets, and that when once adjusted to the individual apparatus its action will thereafter be entirely automatic, requiring no effort nor attention on the part of the operator.

Having thus described my invention, I claim and desire to secure by Letters Patent of the United States, the following:

1. A variable neutralizing condenser, adapted to be operated in conjunction with a tuning condenser, comprising one or more stationary plates, supporting means, electrical connections, an operating shaft, a coupling operatively connecting said operating shaft with the operating means of said tuning condenser, and one or more movable plates adjustably affixed to said operating shaft, each of said plates comprising a series of parallel sectors adapted to be spread fanwise to any desired extent or contacted to the width of a single sector.

2. A variable neutralizing condenser, adapted to be operated in conjunction with a tuning condenser, comprising an operating shaft, a coupling between said operating shaft and the operating shaft of said tuning condenser, one or more movable plates adjustably affixed to said operating shaft, supporting means and electrical connections, together with one or more stationary plates and means operable to vary the spaces between said movable plates and said stationary plates.

3. A variable neutralizing condenser, adapted to be operated in conjunction with a tuning condenser and comprising an operating shaft, one or more movable plates adjustably affixed to said operating shaft, one or more stationary plates adjustably spaced from said movable plates, and means for adjustably coupling said operating shaft with the operating shaft of said tuning condenser, said adjustable coupling means being operable to permit alteration of the angular position of the shaft of said variable neutralizing condenser with respect to the operating shaft of said tuning condenser.

JOHN J. WOOD.
